GRAVE FILLER

Frederick Adam Heise, Luling, Tex.

Application November 18, 1933, Serial No. 698,696

2 Claims. (Cl. 298—24)

This invention relates to a grave filler and has for an object to provide an improved grave filler which is especially useful in quickly and easily filling a grave or other excavation at the proper time.

A further object of this invention is to provide a grave filler consisting of a specially constructed dump wagon or cart which will receive the dirt as the grave or excavation is made and will quickly and easily discharge the dirt back into the grave or excavation when the grave or excavation is to be filled.

Still a further object of this invention is to provide a grave filler which receives the surface soil in a separate hopper from the hopper in which it receives the sub-surface soil so that the surface soil can be discharged last on the top of the excavation or grave, thereby providing a fertile surface for planting flowers or other greenery on the excavation or grave.

Still a further object of this invention is to provide a grave filler which is adapted to receive the dirt as the grave is being dug and then, after the coffin is placed in the grave, to quickly discharge the dirt back into the grave, thus enabling the funeral procession to complete its operations at the grave in a few moments, which is especially desirable during bad weather.

A further object of this invention is to provide a grave filler having a removable, adjustable cover for inclement or rainy weather.

Still a further object of this invention is to provide a grave filler especially useful in small graveyards where there is no professional grave digger or filler present, thus enabling the grave to be filled quickly and easily by the friends and relatives of the deceased.

With the foregoing and other objects in view, as will hereinafter become apparent, this invention comprises the construction, combinations and arrangements of parts, hereinafter set forth, claimed and illustrated in the accompanying drawings:

Fig. 1 is a side elevation of the invention showing the same in operating position.

Fig. 2 is a top plan view of the same, the dirt being removed to clearly show the parts therein.

Fig. 3 is a front view of the grave filler.

Fig. 4 is a rear view of the grave filler.

Fig. 5 is an enlarged sectional view taken on the line 5—5 of Fig. 2.

Fig. 6 is a sectional view taken on the line 6—6 of Fig. 2.

Fig. 7 is an enlarged perspective view showing the fabric connection to the body of the vehicle.

Fig. 8 is an enlarged perspective of a fragment of the agitator.

Fig. 9 is a side elevation of the top portion of the invention showing a covering mounted thereon.

Fig. 10 is a plan view of Fig. 9.

Fig. 11 is an end view looking from the left of Fig. 9.

Fig. 12 is an enlarged fragmentary sectional view of one of the supporting posts.

Fig. 13 is an enlarged section view taken on the line 13—13 of Fig. 10.

Fig. 14 is a view looking from the right of Fig. 13.

There is shown at 10 the grave filler constituting this invention. This grave filler 10 comprises a body 11 mounted on a pair of rear wheels 12 and front wheels 13, the rear wheels 12 being mounted on a rear axle 14 and the front wheels 13 being mounted on a front axle 15, the axle 20 15 being secured to a fifth wheel 16 for supporting the front end of the body 11. A handle 17 secured to the fifth wheel 16 is used in pulling and steering the grave filler 10.

Formed within the body 11 of the grave filler 10 are two hoppers 18 and 19, the hopper 18 having a rearwardly inclined wall 20 at the bottom and of which is hinged a movable floor 21, the movable floor 21 being hinged downwardly at the hinge 22 and moved from opened and closed position and vice versa by means of the rod 23. The operating rod 23 for the lower floor 21 passes through a slot 24 in the rear wall of the body 11 and is held on a catch 25 when it is desired to retain the floor 21 in the forward position.

The hopper 19 consists of a wall 26, to which is hinged as at 27 a bottom floor 28 held in closed position by a rod 29 securable to a catch 30, the catch 30 being secured on the rear wall 31 of the body 11. An agitator 32 consisting of a rod 40 journaled in the opposite side wall of the body 11 and a plurality of fingers 33 therein is operable by a handle 38 outside of the body 11.

In operation the grave filler 10 is placed so that its wheels 12 and 13 are on board tracks 39, 45 each track 39 ending in a stop 40. The tracks 39 are so placed that the stops 40 are positioned at the edge of the grave or excavation 34 that is being dug. The grave filler is then moved along tracks 39 so that it will not overhang the grave or excavation 34 being dug.

Both floors 21 and 28 of hoppers 18 and 19 are placed in closed position by means of their rods 23 and 29. The upper or fertile soil that is first dug from the excavation is placed in the

5 hopper 19, the hopper 19 being of such a size that it will just contain the average amount of upper or fertile soil necessary for growing grass, flowers, or other articles that may afterward be planted on the grave.

10 The hopper 18 will be of such capacity that it will just contain sufficient amount of dirt necessary to complete the filling of the grave. As the grave is dug, the dirt below the upper surface is shoveled into the hopper 18 until the hopper 18 is filled, then an additional amount of dirt is removed equal to the volume that will be occupied by the casket or coffin 35. When the grave 34 is thus prepared, the filled-up grave filler 10 15 is drawn away from the edge of the grave about 3 feet or so, leaving the area of the grave 34 available for the funeral services.

20 When the services are completed and the casket 35 is in position at the bottom of the grave 34, the grave filler is moved backward along the tracks 39 against the stop 40. A screen 36 is then placed about the discharge spouts of the hopper 18 by means of the prepared eyes 37 receiving the hooks 38 on the screen 36. The 25 rod 23 is then detached from the catch 25, permitting the floor 21 of the hopper 20 to drop downwardly to the broken line position shown at 21' in Fig. 5, allowing the dirt in hopper 18 to fall downwardly into the grave 34 over the casket 35. Should this dirt from the hopper 18 become packed or for any reason fail to fall through the discharge spout so formed, the handle 38 of the agitator 32 is rotated causing the prongs of fingers 35 to agitate the dirt and fall through the discharge spout. When the hopper 18 is empty, the hopper 19 is then opened by detaching the holding rod 29 of the floor 28 from the catch 39, thus allowing this dirt to similarly fall through the discharge spout onto the top of the grave, 40 thus providing the usual mound conventionally formed on the top of the grave and likewise providing fertile soil for planting flowers, grass, or other shrubbery thereon.

45 In order to keep the earth in the hoppers 18 and 19 dry in case of rainy or inclement weather, rings 41 are provided to receive and support the poles 43 of an adjustable cover or roof 44, which may be placed thereover, thus preventing the earth in the hoppers from caking and becoming 50 hard to dislodge therefrom.

55 Each pole 43 is provided with a plurality of apertures 45 which will removably receive a dowel pin 46, the pin 46 cooperating with either of the supporting rings 41 and thus hold the pole at the desired height.

60 The upper end of the pole 43 is provided with a universally adjustable end 47 secured thereto by adjustable sections 48 and wing nuts 49 and 50, the wing nut 49 being at right angles to the wing nut 50.

65 The pole end 47 is secured to a plate 51, secured to the framework 52 of the roof 44. It is thus possible to adjust the roof 44 to any desired angle, such as shown at 44' and 44'', thus protecting the earth in the grave filler irrespective of which direction the rain may be coming from.

This grave filler provided by this invention is

intended to be used as one of the tools about a cemetery or graveyard in preparing graves and filling graves, and is especially useful in small cemeteries or graveyards where there are no professional grave diggers employed and where the job of digging and filling the grave must be done by the friends and relatives of the deceased, thus enabling the grave to be filled much more quickly after the funeral ceremonies have been completed while the funeral procession is still present, as is often necessary in such cases.

10 The novel features and the operation of this device will be apparent from the foregoing description. While the device has been shown and the structure described in detail, it is obvious 15 that this is not to be considered limited to the exact form disclosed and that any changes may be made therein within the scope of what is claimed without departing from the spirit of this invention.

20 Having thus set forth and disclosed the nature of this invention, what is claimed is:

1. As an article of manufacture, a grave filler comprising a wagon or cart body, wheels supportably mounting said cart body, a hopper in 25 said cart body comprising a rearwardly inclined front wall, a floor hinged to said front wall, means for holding said floor in closed position, a second hopper formed within said first mentioned hopper, said second hopper comprising an in- 30 clined second front wall and a second floor hingedly secured to said second front wall, and means for detachably holding said second floor in closed position, said second hopper discharging through the opened floor of said first discharged hopper 35 said second floor being of substantially the same area as said first floor and being located substantially vertically above said first floor, whereby the contents of said second hopper may be discharged substantially vertically onto the dis- 40 charged contents of the first hopper.

2. As an article of manufacture, a grave filler comprising a wagon or cart body, said wagon or cart body including opposite side walls and a rear wall, means supportably and movably mounting said cart body, a main hopper formed in said cart body comprising in combination a rearwardly inclined front wall with said opposite side walls and said rear wall, said inclined front wall and said rear wall and opposite side walls forming a discharge spout at the bottom thereof, an openable closure means for said discharge spout, a secondary hopper formed within said first hopper, said secondary hopper comprising a secondary front wall in cooperation with said same 55 rear wall and said same opposite side walls, a secondary openable closure means at the bottom of said secondary hopper, said secondary closure means being of substantially the same area as said main hopper closure means and being located substantially vertically above said main hopper closure means whereby the contents of said secondary hopper may be discharged substantially vertically over the discharge contents of said main hopper.

65

FREDERICK ADAM HEISE.
